COMBINATION DRIP TRAY AND ICE CUBE
STORAGE AND DISPENSING DEVICELester H. Hinkel, Evansville, Ind., assignor to
International Harvester Company, a corpora-
tion of New Jersey

Application November 17, 1950, Serial No. 196,308

6 Claims. (Cl. 62—103)

1

This invention relates to refrigerator cabinets, but more particularly to a unit adapted for storing and dispensing ice cubes therein and additionally arranged for collecting condensate released by a refrigerant evaporator.

In the conventional household refrigerator cabinet there is usually provided a drip tray that is slidably positioned beneath a horizontally extending evaporator for the purpose of catching and collecting any moisture that, otherwise, might drain off the walls thereof and damage the food stored therebelow. During normal operation of the refrigerator the amount of moisture draining into the drip tray is usually very limited and thus a very shallow tray would ordinarily suffice for this purpose. However, during the defrosting cycle the amount of moisture collected in the drip tray is substantial; hence it has been found most desirable to utilize a reasonably deep tray to avoid the possibility of over-spilling during such period. The use of a deep tray is somewhat disadvantageous because the space between the bottom of said tray and the bottom of the evaporator has very little use and, more frequently than not, is wasted. The present invention, therefore, is directed to a device which will permit utilization of this space without interfering with the normal operational function of the drip tray.

The principal object of this invention is to provide a removable drawer-like unit that combines the functions of a drip tray and an ice cube storing and dispensing device in a refrigerator cabinet.

Another important object is to provide an ice cube storing and dispensing device that is positionable in close proximity to an evaporator unit in a refrigerator cabinet.

A further object is to provide a refrigerator evaporator drip tray that includes means for storing ice cubes therein and for dispensing said cubes therefrom as desired.

A still further object is to provide a rotatable ice cube storing and dispensing device suitable for mounting in a refrigerator evaporator drip tray.

A yet still further object is to provide a wheel-like partitioned or grid member, pivotally mounted in a refrigerator evaporator drip tray, that is adapted for storing ice cubes and manually rotatable for dispensing said cubes through an opening in the tray.

Another object is to provide a combination drip tray and ice cube storing and dispensing device that is adapted for removable mounting directly beneath and in close proximity to the outer bot-

2

tom surface of a household refrigerator evaporator.

Further objects and advantages of the present invention will be apparent from the full description, reference being had to the accompanying drawing wherein a preferred form of the present invention is clearly shown:

Fig. 1 is a front view of a conventional refrigerator cabinet, with the door removed, in which the proposed invention has been incorporated.

Fig. 2 is a perspective view of the combined drip tray and ice cube storing and dispensing device of the present invention.

Fig. 3 is a top plan view of the device shown in perspective in Fig. 2.

Fig. 4 is a sectional view taken on line 4—4 of Fig. 3.

Fig. 5 is an enlarged fragmentary section of one side of the tray and shows the sliding means for guiding the tray beneath the evaporator.

In a preferred embodiment, illustrated in the accompanying drawings, the invention is shown incorporated in a conventional front-opening type refrigerator cabinet indicated generally by the numeral 10. As is well understood in the art such cabinets generally include an inner liner that provides inner walls 11 and forms a food storage compartment 12, and an outer liner

spaced therefrom that provides outer walls 13. A horizontally extending refrigerant evaporator unit 14, positioned in the upper portion of the food storage compartment 12, is usually provided with a pivotally mounted door 15. Since the remaining details of the cabinet and of its associated refrigerating apparatus are not particularly essential to the present invention, no attempt has been made to show them in the drawings and no further description thereof will be had.

In accordance with the proposed invention 16 is a liquid tight drawer-like tray or container having a bottom wall 17, upstanding side walls 18, a rear wall 19 and a front wall 20. The bottom wall may, if desired, be pitched as shown toward a drain opening 17a that ordinarily would be closed by a plug 17b of suitable material such as rubber or the like. Such tray or container may be of any suitable material, but preferably, it is fashioned from one of the many plastics well known in the art suitable for this purpose. It is dimensioned, preferably, so as to slightly overlap the exterior horizontal dimensions of the evaporator 14. The tray is adapted for slidable positioning beneath the evaporator in any suitable manner such as, for instance, by means of

55

the horizontally extending rib-like member 21 preferably fashioned integrally with the side wall 18 and further adapted for slidable mounting in a channel member 22, in turn, affixed by any suitable means to the side wall 11 of the cabinet inner liner. A similar rib and channel, it will be understood, will likewise be provided for the opposite side wall.

Projecting upwardly from the floor 17, of the tray 16, is a pedestal 23 into which has been fixedly mounted a pivot pin 24 that projects outwardly therefrom for reasons which will be presently explained. Concentrically arranged and radially spaced with respect to said pedestal 23 and projecting upwardly from the floor of said tray is a ring-like ledge or shelf 25, which, like the pedestal, preferably is fashioned integrally with said floor, but if desired, may be separately fabricated and then suitably affixed thereto. The upper surface 25a of said shelf, preferably, is slightly crowned for reasons which presently will appear. An opening 26 in said ledge 25 cooperates with an outwardly extending lip portion 27, of the floor of said tray, to form a chute-like passage 28 the opposite end of which connects with an opening 29 in the front wall 20 of the tray to provide a passage between the inside and outside of the tray.

A partitioned wheel-like turntable or grid dispenser member, indicated generally by the numeral 30, includes a central pivot post 31 with an opening 32 therethru, and a cup-shaped member having a flat circular portion 33 from the peripheral edge of which depends an annular ring or flange 34. Concentrically arranged with respect to said flange member 34 and radially spaced therefrom is a vertically disposed ring 35 which is connected thereto by the radially extending, axially disposed and circumferentially spaced partition members 36. Concentrically arranged with respect to the circular ring 35 is a channel shaped wall member 37, which, in turn, is connected to said ring by similar circumferentially spaced partition members 36. This wheel-like grid member or turntable, as in the case of the drip tray, is fashioned, preferably, from one of the many well known plastics. The external dimensions of this circular dispenser, it is understood, will, of course, be governed by the dimensions of the drip tray, but the dimensions of the individual partitioned compartments will be governed by the dimensions of the ice cubes used therewith. An opening 38 in the front vertical wall of the tray 16, is provided so that a portion of the outer periphery of the circular dispenser may project therethrough, after said dispenser member has been pivotally mounted around the pin 24, and thus facilitate the manual operation of the dispenser.

In using the invention the circular dispenser is pivotally positioned in the tray and the assembly then slidably positioned beneath the refrigerator evaporator so that any moisture draining off said evaporator may be collected in the tray. The collection of such moisture in no wise interferes with the use of the device as a storage and dispensing device for ice cubes because the cubes are stored on the top of the shelf or ledge which is spaced from the floor of the tray. In the use of the invention for storing and dispensing purposes ice cubes 39 may be placed in the small compartments formed in the circular dispenser and bounded by the radial partition and the ring members, and, the cubes, when so positioned, will rest on the crowned top 25a, of the upstanding

ledge 25. As the ice cubes are desired by the user the circular wheel-like dispenser 30 is manually rotated by turning the portion of the periphery thereof that projects through the front wall of the tray, whereupon the cubes are pushed along the top surface of the ledge 25 till one of the compartments, and the cube therein, comes into vertical alignment with the opening 26, in said ledge, whence the cube will drop into the chute 28 and out through the front opening 29. The crowned surface 25a, on the ledge 25, will facilitate drainage of any moisture from the ice cubes into the tray before reaching the opening 26.

It will now be appreciated that the present invention provides a very simple and effective removable drawer-like unit that not only permits more efficient utilization of otherwise wasted storage space in a refrigerator cabinet for storing ice cubes but also incorporates into said unit a means for dispensing said cubes as well as a means for collecting moisture or condensate as it drains off a refrigerator evaporator. Since the ice cubes will be stored in close proximity to the low temperatured evaporator unit there will, of course, be no substantial melting of the cubes before use. In the event, however, some melting of the cubes should be experienced there will be no damage to the food in the compartment below because the resulting moisture will drain directly into the liquid tight drip tray.

Although only a preferred form of the invention has been illustrated, and that form described in detail, it will be apparent to those skilled in the art that various modifications may be made therein without departing from the spirit of the invention or from the scope of the appended claims.

What is claimed is:

1. A drawer-like device of the class described, comprising: a container having a bottom with upstanding side, end and front walls secured thereto and having the top open; the front wall of said container being fashioned with an opening therein; a circumferentially extending shelf within said container; said shelf being fashioned with an opening therethrough which is arranged to register with said front wall opening to provide a chute-like passage from the inside to the outside of said container; a circular grid member pivotally mounted in said container in spaced relation to said shelf; said grid member being fashioned so as to provide a plurality of open-ended cells adaptable for receiving individual ice cubes therein; and having said grid member disposed so that each cell therein may be rotatably brought into registration with the opening in said shelf whereby an ice cube positioned in the cell may be released and discharged through said opening.

2. An article of the class described, comprising: a drawer-like container having a bottom wall and upstanding side, end and front walls affixed thereto with the top thereof open; the front wall of said container being fashioned with an opening therein; a circumferentially extending shelf horizontally disposed within said container and spaced from the bottom wall thereof, the upper surface of said shelf being slightly crowned; said shelf being fashioned with an opening therethrough which is positioned so as to register with the opening in said front wall to provide a chute-like passage from the inside to the outside of said container; a circular grid member pivotally mounted within said container

in spaced relation to said shelf; said grid member being fashioned so as to provide a plurality of open-ended cells adaptable for receiving individual ice cubes therein; and having said grid member disposed so that each cell therein may be rotatably brought into registration with the opening in said shelf, whereby an ice cube positioned in the cell may be released and discharged through said opening.

3. An article of the class described, comprising: a drawer-like container having a bottom wall and upstanding side, end and front walls with the top thereof open; the front wall of said container being fashioned with an opening therein; a circumferentially extending shelf horizontally disposed within said container and spaced above the bottom wall thereof, the upper surface of said shelf being slightly crowned; said shelf being fashioned with an opening therethrough which is positioned so as to register with the opening in said front wall to provide an inclined chute-like passage between the inside and outside of said container; a flat circular grid member pivotally and horizontally mounted in said container in axial alignment with but spaced from the upper crowned surface of said shelf; said grid being fashioned so as to provide concentric rings of circumferentially spaced compartments adapted to receive and maintain ice cubes in spaced relation therein; said grid being arranged so that each compartment therein may be rotatably positioned above and in registration with the opening in said shelf, whereby an ice cube positioned in the compartment may be released and discharged through said opening.

4. In a refrigerator cabinet having inner and outer walls and an evaporator unit mounted upon said inner walls, the combination, comprising: a liquid container having the top thereof open and having an opening provided in one wall thereof; said container being slidably mounted below and in close proximity to the evaporator unit whereby condensate drained off said unit may be collected in said container; said container having a circular upwardly projecting rib disposed therein and secured to the bottom wall thereof; said rib being fashioned with an opening therethrough which is positioned so as to register with the opening in said wall to provide a chute-like passage between the inside and outside of said container; a turntable pivotally mounted in said container in parallel spaced relation to said rib member; said turntable member being fashioned so as to provide a plurality of circumferentially spaced and concentrically arranged open-ended cells therein; and having said turntable disposed so that ice cubes placed in the cells thereof will rest on said circular rib until said turntable is rotated so as to bring each of said cells in registration with the chute opening

whereupon the ice cube in each cell will be released and discharged through the wall opening.

5. In a refrigerator cabinet having inner and outer walls and an evaporator unit mounted upon said inner walls, the combination, comprising: a drawer-like unit disposed beneath an evaporator; means for slidably mounting said drawer unit in close proximity to the evaporator; said drawer unit having two openings in one wall thereof; a turntable pivotally mounted within said drawer unit; said turntable being arranged so that a portion of the periphery thereof projects through one of the openings in said drawer wall whereby said unit may be manually rotated; 10 said turntable member being fashioned so as to provide a plurality of open-ended cells therein adapted to receive individual ice cubes; and having said turntable disposed so that each cell therein may be rotatably selectively brought into registry with the other of said openings in said drawer wall, whereby the ice cube in an individual cell may be released and discharged through said opening.

6. An article of the class described, comprising: a drawer-like container having a bottom wall and upstanding side, end and front walls affixed thereto with the top thereof open; the front wall of said container being fashioned with an opening therein; means serving as a shelf circumferentially extending and horizontally disposed within said container and above the bottom wall thereof; said shelf means being fashioned with an opening therethrough positioned to register with the opening in said front wall 20 to provide a chute-like passage from the inside to the outside of said container; a flat circular grid member pivotally mounted in said container in axial alignment with said shelf means but spaced from the upper surface thereof; said grid being 25 fashioned so as to provide concentric rings of circumferentially spaced compartments adapted to receive and maintain in spaced relation therein ice cubes positioned on said shelf means; said grid being arranged so that each compartment 30 therein may be rotatably positioned above and in registration with the opening in said shelf means, whereby ice cubes positioned in these compartments may be selectively released and discharged through said opening.
